DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

RESCHEDULING OF I/O INTERRUPTS

Gerald A. Davison, Poughkeepsie, and Edward J. Nauss, Millbrook, N.Y., assignors to International Business Machines Corporation, Armonk, N.Y.
Continuation of application Ser. No. 218,743, Jan. 18, 1972. This application July 25, 1973, Ser. No. 382,431

Int. Cl. G06f 7/00

U.S. Cl. 444—1

13 Sheets Drawing, 32 Pages Specification

To evaluate computer system performance, software techniques are frequently used to collect data on the system as it runs, and/or to simulate new devices. However, data collecting, simulating and report writing procedures degrade the performance of the system on which they are run and therefore provide distorted results. The technique herein is designed to hide the overhead procedure from the performance of the system by using prior art procedures in stopping the system clock whenever an overhead program is being executed, and adding to that a technique for compensating for distortion in the I/O area by intercepting and rescheduling I/O interrupts to compensate for the "stolen" time during which the system clock is stopped.

The procedure involves the interception of all I/O instructions issuing from the CPU to the channel and interception of all I/O interrupts from the channel in order to reschedule their presentation to the operating system. This is accomplished by measuring the length of time that it takes for the I/O operation to be performed and, by adding to that time any "stolen" time taken from the operating system during the period in which the I/O operation was outstanding, the presentation of the interrupt may be delayed an appropriate time. Provision is made for scheduling the interrupt in accordance with the above calculation, and provision is also made for further delaying the interrupt if additional time is taken between initial rescheduling and final presentation.

13 Sheets-Sheet 11

FIG. 8

IOICB

TEBCHN X '00'	USED FOR CHAINING BLOCKS TOGETHER	
TEBTME	CONTAINS DELTA TIME WHEN BUILT, LATER CONTAINS SIMULATED TIME OF INTERRUPT	
TEBRTN	ADDRESS OF ROUTINE TO PROCESS EVENT WHEN IT OCCURS	
IOICBCSW	CSW FOR I/O INTERRUPT	
CSW (CONTINUED)		
IOICBDVC UNIT ADDRESS OF INTERRUPTING DEVICE	IOICBFB FLAGS	NOT USED

FIG. 9A

IOOCB

(FORMAT FOR OS OPERATION FROM TRAPPED SIO)

CPCBCHN	RESERVED FOR I/O SCHEDULER TO CHAIN IOICB'S TOGETHER	
NOT USED	CPCBFLGS FLAGS	NOT USED
CPCBCAW I/O PROTECT KEY	CHANNEL PROGRAM ADDRESS	
CPCBRTIM	VALUE OF REAL TIME CLOCK AT SIO - VALUE OF SIMULATED TIME CLOCK AT SIO ($E_{R,SIO} - E_{S,SIO}$)	

Jan. 22, 1974

RESCHEDULING OF I/O INTERRUPTS

Original Filed Jan. 18, 1972

13 Sheets-Sheet 12

FIG. 9B

IOOCB

(FORMAT FOR INTERCEPTOR I/O OPERATIONS)

CPCBSENS CPCBCHN	SENSE DATA	
	CPCBFLGS FLAGS	CPCBECB RELATIVE ECB NUMBER
CPCBCAW I/O PROTECT KEY	CHANNEL PROGRAM ADDRESS	
CPCBCSW	CSW	
	CSW	
CPCBPCI NOT USED	PCI APPENDAGE ROUTINE ADDRESS (OPTIONAL)	

FIG. 10

DVCB

(DEVICE CONTROL BLOCK)

DVCBCHN X'00'	POINTER TO LCB OR IOOCB	
DVCBUNAD	UNIT ADDRESS	DVCBFLGS FLAGS
DVCBCOCCB COCCB POINTER	DVCBROT ROTATION TIMING POINTER	DVCBHASH HASH POINTER
BELOW IS AN ALTERNATE FORMAT OF THE DVCBCHN FIELD		
X'FF'	NOT USED	DVCBECB RELATIVE ECB NUMBER

13 Sheets-Sheet 13

FIG. 11

CHCB
(CHANNEL CONTROL BLOCK)

CHCBPEND X '00'	POINTER TO 1ST PENDING IOICB		
CHCBFLGS FLAGS	CHCBSIMB CHANNEL SIMULATED BUSY	CHCBOS SIMULATED BUSY, REALLY BUSY, OS INTERRUPT EXPECTED, OS USED LAST	CHCBTPD REALLY BUSY, INTERCEPTOR USED LAST
CHCBQLEN CHANNEL QUEUE LENGTH	CHCBSM SYSTEM MASK BIT FOR CHANNEL	CHCFCUB CONTROL UNIT BLOCKAGE COUNT	
CHCBQ	CHANNEL QUEUE ENTRY NUMBER OF QUEUE ENTRIES = ONE FOR OS + ONE FOR EACH INTERCEPTOR DEVICE		

FIG. 12

COCB
(CONTROL UNIT CONTROL BLOCK)

COCLBLID	POINTER TO A CHAIN OF IOICB'S FOR LOCKED BID KEYS		
COCBFLGS FLAGS	COCBBASE CONTROL UNIT BASE ADDRESS	COCBFLGX FLAGS
